(57) **CLAIM**

The ornamental design for a touch screen control device with speakers, as shown and described.

DESCRIPTION

FIG. 1 illustrates a front view of a touch screen control device.

FIG. 2 illustrates a right side view of the touch screen control device of FIG. 1.

FIG. 3 illustrates a top view of the touch screen control device of FIG. 1.

FIG. 4 illustrates a bottom view of the touch screen control device of FIG. 1.

FIG. 5 illustrates a left side view of the touch screen control device of FIG. 1.

FIG. 6 illustrates a back isometric left view of the touch screen control device of FIG. 1.

FIG. 7 illustrates a back isometric right view of the touch screen control device of FIG. 1.

FIG. 8 illustrates a rear view of the touch screen control device of FIG. 1; and,

FIG. 9 illustrates a front isometric view of the touch screen control device of FIG. 1.
